CLAIM

The ornamental design of a saucer, champagne glass and cup set, that as shown and described.

DESCRIPTION

FIG. 1 is a perspective view of a saucer in accordance with the subject invention;

FIG. 2 is a front elevational view of the saucer;

FIG. 3 is a rear elevational view of the saucer;

FIG. 4 is a right side elevational view of the saucer;

FIG. 5 is a left side elevational view of the saucer;

FIG. 6 is a top plan view of the saucer;

FIG. 7 is a bottom plan view of the saucer;

FIG. 8 is a perspective view of a champagne glass in accordance with the invention;

FIG. 9 is a front elevational view of the champagne glass;

FIG. 10 is a rear elevational view of the champagne glass;

FIG. 11 is a right side elevational view of the champagne glass;

FIG. 12 is a left side elevational view of the champagne glass;

FIG. 13 is a top plan view of the champagne glass;

FIG. 14 is a bottom plan view of the champagne glass;

FIG. 15 is a perspective view of a cup in accordance with the invention.

FIG. 16 is a front elevational view of the cup;

FIG. 17 is a rear elevational view of the cup;

FIG. 18 is a right side elevational view of the cup;

FIG. 19 is a left side elevational view of the cup;

FIG. 20 is a top plan view of the cup;

FIG. 21 is a bottom plan view of the cup; and,

FIG. 22 is a perspective view of a saucer, champagne glass and cup set in accordance with the subject invention.
